UNITED STATES PATENT OFFICE.

STEPHEN D. STACKHOUSE, OF GLENLYON, PENNSYLVANIA.

FLY-WHEEL JACK.

1,082,452.

Specification of Letters Patent.

Patented Dec. 23, 1913.

Application filed March 26, 1913. Serial No. 756,912

To all whom it may concern:

Be it known that I, STEPHEN D. STACKHOUSE, a citizen of the United States, residing at Glenlyon, in the county of Luzerne 5 and State of Pennsylvania, have invented new and useful Improvements in Fly-Wheel Jacks, of which the following is a specification.

This invention relates to improvements in 10 manually operated devices for rotating the fly wheels of engines to throw the latter off dead center and has particular application to what are commonly termed fly wheel jacks.

15 In carrying out the present invention, it is my purpose to provide a jack of the class described whereby engine fly wheels, driving pulleys and the like may be thrown off dead center so as to facilitate the starting of the 20 engine. It is also my purpose to provide a fly wheel jack which will embrace the desired features of simplicity, efficiency, durability and convenience and which will be composed of few parts and these so arranged 25 and correlated as to reduce the possibility of derangement to a minimum and furthermore, my improved jack may be folded and stored in a comparatively small space.

With the above and other objects in view, 30 the invention consists in the construction, combination and arrangement of parts hereinafter set forth in and falling within the scope of the claim.

In the accompanying drawing; Figure 1 35 is a top plan view of a jack constructed in accordance with my present invention. Fig. 2 is a side elevation of the same, and Fig. 3 is a view in elevation of the jack and the fly wheel showing the manner of using the jack 40 to rotate the fly wheel.

Referring now to the accompanying drawing in detail the numeral 1 designates a standard constructed in any suitable manner of any desired or necessary dimensions, such 45 standard having the upper end thereof preferably forked or bifurcated as at 3 and the limbs of such bifurcated portion formed with alining apertures designed to receive a pivot bolt 4. Pivotaly mounted upon the 50 bolt 4 between the limbs of the forked extremity of the standard 1 is an operating lever having a short arm 5 and a relatively long arm 6 whereby the power applied to the long arm will be multiplied when trans-

mitted to the short arm 5. Pivotaly connected to the free end of the short arm of the operating lever is one extremity of a link 7 equipped with pivot pins 8, 8, spaced apart along the length of the link and having pivoted thereon jaws 9, 9 formed with laterally extending gripping fingers 10. The confronting edges thereof being beveled or inclined, the jaws 9, 9 will rest in a plane parallel with that of the link, as clearly illustrated in Fig. 2, while, in the use of 65 the jack, as shown in Fig. 3, the jaws will be disposed one above the other.

In the application of the jack to a fly wheel, as shown in Fig. 3, the gripping fingers 10, 10 are disposed upon the inner 70 and outer walls of the rim of the wheel and the arm 6 of the operating lever moved in a vertical direction so that the jaws 9, 9 will be disposed one above the other and grip the fly wheel at a point a suitable distance below 75 the fulcrum of the operating lever whereby, when the relatively long arm of the operating lever is pulled downwardly, the jaws will effectively grip the rim of the wheel and impart a rotary movement thereto so as to 80 throw the wheel off of dead center. Should it be desired to rotate the fly wheel several times, it will be seen that the long arm 6 of the operating lever will be moved up and down several times thereby throwing the 85 jaws downwardly and upwardly so that such jaws can grip the fly wheel at a lower point each time they move in a downward direction.

I claim:

90 A device of the class described comprising a standard, an operating lever fulcrumed upon the upper extremity of said standard and having a short arm and a relatively long arm, a link pivoted at one end to the 95 free extremity of said short arm and provided with pivot pins extending outwardly from one face thereof and spaced apart, and jaws mounted upon said pivot pins and having the front edges thereof beveled and 100 the opposite ends extended outwardly to form gripping fingers.

. In testimony whereof I affix my signature in presence of two witnesses.

STEPHEN D. STACKHOUSE.
